UNITED STATES PATENT OFFICE.

ALFRED H. HUMPHREY, OF KALAMAZOO, MICHIGAN.

IGNITER.

SPECIFICATION forming part of Letters Patent No. 705,673, dated July 29, 1902.

Application filed June 26, 1900. Serial No. 21,693. (No model.)

To all whom it may concern:

Be it known that I, ALFRED H. HUMPHREY, a citizen of the United States, residing at the city of Kalamazoo, in the county of Kalamazoo and State of Michigan, have invented certain new and useful Improvements in Igniters, of which the following is a specification.

This invention relates to improvements in automatic igniter apparatus for cluster gas-burners and to automatic igniters generally.

The objects of my invention are, first, to provide an improved automatic igniter for a cluster of gas-jets; second, to provide an improved means of igniting a cluster of gas-jets from a central point; third, to provide an improved automatic ignition device for gas-jets, whereby the spongy platinum is retained and protected in the proper position to receive the jet of gas from an auxiliary jet or burner; fourth, to provide an improved automatic auxiliary igniter for gas-jets.

Further objects will definitely appear in the detailed description to follow.

I accomplish the objects of my invention by the devices and means described in this specification.

The invention is clearly defined and pointed out in the claims.

A structure embodying my invention is clearly illustrated in the accompanying drawings, forming a part of this specification, in which—

Figure 1 is an elevation of a cluster gas-light or chandelier with my improved igniter apparatus in position. Fig. 2 is a plan view of the same, the supply-pipe being shown in section, the holder H being removed. Fig. 3 is a detail view, partially in section, on line 3 3 of Fig. 2, showing details of construction of my improved igniter and the method of inserting the same into the supply-pipe of a chandelier or cluster. Fig. 4 is a detail sectional view through the holder of the automatic igniter, taken on line 3 3 of Fig. 1, the branches from the burner being shown in full lines. Fig. 5 is a detail view of the valve and connection to the igniter portion. Fig. 6 is a detail sectional view on line 6 6 of Fig. 3, showing details of the auxiliary burner. Fig. 7 is a detail view of a modification of the connection from the center jet to the various

burners of the cluster, in which perforations are utilized in place of slits in the connecting-tubes.

55

In the drawings all of the sectional views are taken looking in the direction of the little arrows at the ends of the section-lines.

Similar letters of reference refer to similar parts throughout the several views.

60

Referring to the lettered parts of the drawings, A is the central supply for the cluster or chandelier and is provided with branching tubes A' A', leading to each burner A'' A'' of the cluster, six being illustrated in this connection, each being of the usual construction of Welsbach burners, having chimneys B B of the usual form. A valve with lever and chain is provided for controlling the supply of gas to these burners.

70

Inserted into the central connection A is a combination T and elbow coupling or fitting, the elbow pointing upward in the direction of the central coupling. The gas-supply pipe G is inserted into the top of the T and supplies gas both to the chandelier or cluster and to the igniter apparatus. A smaller tube or pipe C' connects to the elbow coupling or fitting C and extends upwardly. This is provided with a small valve held normally closed by a spring a, coiled upon the stem of the same and connected to the screw or stud n'.

75

A chain J is attached to the lever m and depends downward to be pulled when it is desired to ignite the burners. In the preferred construction this chain passes through a loop L' on the lever L, and the downward pull on the chain brings the button or stop J' in contact with the lever L, and the supply-valve to the jets or burners is opened at the same time. When the chain is released, the spring a closes the igniter-valve. The valve is limited by stops r striking the pin or screw n. A small Bunsen burner E is provided above this valve, having passages s for the gas to mix with air. A central tube E' extends above the top of the Bunsen burner and delivers gas unmixed with air upon a spongy platinum or other suitable metal or compound or combination of materials to ignite it automatically. This ignition material is contained within a tube H, having apertures H' around the same for the free admission of air. Little fingers are formed by the slots H' at the bot-

80

100

tom, which enables this tube H to be placed upon the little head F and be retained in position. The head F is connected to the top of the burner E, and from it radiate small tubes or 5 pipes F', pointing toward the various burners of the cluster, the tubes F' approaching the chimneys without extending over them and are situated considerably above the chimneys, as appears in Fig. 1. If they are located 10 at any point above the chimney within reach of the same, so that the flames therefrom will be projected above the top of the chimney, that is all that is required for effective service, though as I have arranged the tubes it 15 will be found most satisfactory, because with the jets lower down they may heat the chimneys and crack them. Along the upper side of each tube F', I provide a restricted aperture—either a slit F', extending to the center of 20 of the head F, or a series of perforations F''—in close proximity to each other. These are to pass the flames from the central or auxiliary jet or igniter out to the ends of the tubes, so that they will be delivered over the top of 25 each chimney to ignite each burner of the cluster.

From this description of parts the operation of my improved cluster-igniter must be obvious. The chain J is pulled, which admits gas to the burners of the cluster and also 30 to the small Bunsen burner E, and also a current of undiluted gas passes up through the tube E' and is directed against the igniter material I. This being platinum or any suitable composition or combination of materials 35 ignites the jet of raw gas, and this ignites the mixture of air and gas coming up from the Bunsen burner, and as the passages therefrom are restricted this current is forced to 40 carry outwardly through the tubes F' and is ignited along the same through the restricted apertures F'' or F''', so that the flame is delivered as a jet outwardly over the top of each burner, and each burner is consequently 45 lighted. When this is accomplished, the chain J is released, the spring a cuts off the supply of gas to the igniter apparatus, and the burners continue to burn until the gas is shut off in the usual way. Where desirable, the chain 50 J is not connected to the lever L in any manner, and the device is then operated by pulling the chain J, which operates the igniter, as before described. The gas is then turned onto the burners in the usual way, and when all 55 are ignited the chain J is released and the igniter-valve is closed.

I have described my improved igniter in detail, as I believe it is the best form for accomplishing the desired end. I desire, however, 60 to remark that the structure is capable of great variation in its formation and arrangement, and I wish also to claim the features which I have illustrated broadly. I am aware that the

principle is applicable to single burners and 65 wish to claim such also. I also desire to remark that I am aware that it is not necessary to surround the igniter material I by a tube H, but that any convenient support might be provided to hold the igniter in this position.

Having thus described my invention, what 70 I claim as new, and desire to secure by Letters Patent, is—

1. In an igniter for a cluster of gas-burners, the combination of a coupling C for insertion into the gas-supply passage; an upwardly- 75 extending pipe C' therefrom; the Bunsen burner; a valve held normally closed by a spring; a chain or connection J for opening the same; a tube E' extending up within the Bunsen burner to deliver a jet of undiluted 80 gas; a tube or holder H and an igniter compound I supported within the tube or holder in the jet of undiluted gas; a head F embracing the top of said Bunsen burner having radiating tubes or passages F' therefrom with 85 restricted passages along the top thereof to carry the flame out to the ends of the same and deliver it in jets at each burner of the cluster, all coacting substantially as described for the purpose specified. 90

2. In an igniter for chandeliers or a cluster of burners, the combination of a central Bunsen burner; a passage for undiluted gas; an igniter material supported within such undiluted-gas jet; and tubes leading from the 95 central Bunsen burner laterally toward the burners of the cluster or group and containing restricted apertures along the same to carry the flame outwardly to the ends to ignite the burners of the group, for the purpose 100 specified.

3. In an igniter for chandeliers or cluster-burners, the combination of a central auxiliary burner; an igniter material supported within the jet of said auxiliary burner; and 105 tubes leading from the auxiliary burner laterally toward the burners of the cluster or group, the said tubes containing restricted apertures to carry the flame outwardly to ignite the burners of the group, as specified. 110

4. In an igniter for chandeliers or cluster-burners, the combination of a central auxiliary burner; an igniting means for such burner; tubes leading from the auxiliary burner laterally toward the several burners 115 of the cluster or group, the said tubes containing restricted apertures to carry the flame outward to ignite the burners of the group.

In witness whereof I have hereunto set my hand and seal in the presence of two witnesses. 120
